UNITED STATES PATENT OFFICE.

JOHN L. CREVELING, OF NEW YORK, N. Y., ASSIGNEE TO SAFETY CAR HEATING AND LIGHTING COMPANY, A CORPORATION OF NEW JERSEY.

ELECTRIC REGULATION.

1,308,983.

Specification of Letters Patent.

Patented July 8, 1919.

Application filed April 19, 1911. Serial No. 621,998.

To all whom it may concern:

Be it known that I, JOHN L. CREVELING, a resident of the city, county, and State of New York, have invented certain new and 5 useful Improvements in Electric Regulations, as set forth in the annexed specification and drawing forming a part thereof.

My invention pertains to that class of electric regulation wherein a dynamo or generator 10 or is automatically regulated to charge a storage battery.

My invention has for its particular object to provide means for automatically charging a storage battery, the voltage of which remains 15 substantially constant throughout charging and when in a charged condition and it is no longer necessary to continue the full charging rate.

Figure I of the drawing is a diagrammatic representation of one type of system embodying the essentials of my invention.

Fig. II is a modification which may be made in the system of Fig. I.

In Fig. I, 1 represents a generator provided with the usual field coil 2 which may be controlled as by the variable resistance 3 in this instance indicated as of the carbon pile variety for sake of simplicity merely. 4 is a lever normally drawn in an upward 20 direction as by the adjustable spring 5 in such manner as to tend to compress the carbon pile 3 and reduce the resistance thereof. The lever 4 is provided at one extremity with the core of magnetic material 6 and 25 motion given to the said core may, therefore, regulate the resistance 3. 7 represents the positive lead of the generator which is carried to one side of the switch 8 in this instance indicated as of the usual automatic 30 variety. The opposite terminal of the switch 8 is connected with the main 9 communicating with the positive side of the storage battery 10 and the positive terminals of the translating devices 11. The 35 translating devices 11 have their negative terminals connected with the lead 12 which is carried through the solenoid 13 to the negative brush of the generator. The negative side of the storage battery 10 is connected 40 with the lead 12 through the adjustable resistance 14. From one side of the adjustable resistance 14 the wire 15 is carried to one brush in connection with the armature 16, the opposite brush of which is connected 45 to the lead 12 in such manner that the meter 50

armature 16 is in shunt around the adjustable resistance 14. 18 is a permanent field magnet setting up a magnetic field for the armature 16. The armature 16 is arranged to move very freely as, for example, carried 55 in pivot bearings as indicated and is provided with a worm 19 engaging the worm-wheel 20 provided with the pinion 21 driving a train of gears as indicated at 22 and 23. The gear 23 is provided with a smooth 60 hub 24 adapted to frictionally engage the friction wheel 25 carried by the lever 26 and normally drawn in a direction away from the hub 24 by the adjustable spring 27. The friction wheel 25 is provided with an arm 65 28 normally drawn against the stop-pin 29 by the adjustable spring 30 engaging one extremity of the arm 28. The arm 28 carries at one extremity a contact member 31 insulated therefrom and adapted to cause electrical communication between the contact members 32 and 33. The contact member 32 is connected with the lead 12 and the member 33 is connected as by the wire 34 with one end of the high resistance solenoid 35, 70 the opposite end of which is connected with the lead 7 as indicated. The electromagnet 37 is placed in shunt across the battery 10 as by wires 38 and 39.

The operation of my invention is substantially as follows, referring particularly to Fig. I:

If the switch 8 be closed and the generator running at a voltage sufficient to supply current to the storage battery 10 and to the 90 lamps or other translating devices and if 7 be the positive lead of the generator, current will flow through the lead 7, switch 8 and lead 9 to the battery and return through adjustable resistance 14, lead 12 and solenoid 95 13 to the generator. If any of the translating devices 11 be in circuit, current will flow through the same from the lead 9 to the lead 12. I now so adjust the spring 5 that when the desired maximum current is delivered by the generator any appreciable increase in this current will draw the core 6 downwardly against the action of spring 5 in such manner as to increase the resistance 3 and prevent this desired maximum current from being exceeded. The current delivered to the battery and flowing through the adjustable resistance 14 will cause a difference of potential across the said resistance which will be a function of the current 110

flowing therethrough. This difference of potential will cause current to flow through wire 15, armature 16 and wire 17 around the resistance in a well-known manner and as the 5 field magnet 18 provides a substantially constant magnetic field of uniform polarity, the direction of rotation of the armature 16 will depend upon the direction of the difference of potential across the resistance 14 which, 10 in turn, will depend upon the direction of flow of current through the resistance 14—that is, whether current be flowing into the battery or out of the same, and as the magnetic field of the armature 16 remains constant 15 the velocity of rotation of the armature 16 will be a function of the drop across the resistance 14 and its direction of rotation will depend upon the direction of the current through 14; therefore, the current above 20 taken as flowing into the battery will cause the armature 16 to revolve in a given direction with a velocity dependent upon the value of said current. This rotation of the armature will revolve the worm 19 and the 25 train of gears 20, 21, 22 and 23 and the friction hub 24, and I so arrange the connection of the armature 16 that when charging current is flowing to the battery, the direction of the rotation of the armature 16 is such 30 that the hub 24 moves in a clockwise direction and I so adjust the spring 27 that if the batteries are at or above their normal voltage, the current flowing from the lead 9 through the wire 39, magnet 37 and wire 38 35 attracts the lever 26 and holds the friction wheel 25 in operative contact with the friction hub 24. Therefore, as the charging current is delivered to the battery the revolution of the armature 16 causes the friction wheel 40 25 to slowly revolve in counter-clockwise direction depending upon the current delivered to the battery and thus causes the lever 28 to approach contacts 32 and 33 with a velocity dependent upon the current being delivered 45 to the battery. If now the charging current fall to zero, the armature 16 will cease to revolve and the lever 28 will remain stationary. If current be used from the battery the same will flow through the resistance 14 in 50 an opposite direction from the charging current and cause the armature 16 to revolve in a reverse direction and move the lever 28 away from the contacts 32 and 33 with a velocity depending upon the rate of current taken from the battery. If, of course, the 55 efficiency of the battery were 100 per cent. and the performance of its measuring devices theoretically perfect, then a given charge delivered to the battery would move the lever 28 a given distance in one direction and an equal discharge would move the lever back the same distance in an opposite direction, and the charge of the battery could be determined at any time by the position of 60 the lever. However, as these conditions are far from met in practice, I so arrange the lever 26 and its magnet 37 and spring 27 that when the voltage of the battery falls slightly below its normal voltage, the spring 27 may move the lever sufficiently to break 70 the operative contact between the hub 24 and the friction wheel 25 and allow the lever 28 to resume the position shown in the drawing under the influence of spring 30. Therefore, if the charging current be continued 75 until the battery has had forced thereinto the desired charge and the contacts 32 and 33 so positioned that when this desired charge has been delivered to the battery the contact member 31 will cause communication between 80 32 and 33 and then current will flow from the lead 7 through the solenoid 35, wire 34, contacts 33, 31, 32 to the lead 12 and the coil 35 is so wound as to assist the coil 13 and lower the charging rate by lowering the current delivered by the generator in a well-known manner, and it is obvious 85 that this rate may be cut down as much as desired by proper arrangement and proportioning of the coil 35. If now current be 90 taken from the battery as, for example, in case the translation circuit load be increased beyond the current now delivered by the generator, the current flowing from the battery through the resistance 14 will cause the armature 16 to revolve in such direction as to move the lever 28 in a clockwise direction and after moving in this direction the contact at 33—31—32 will be broken and the generator will deliver its full normal output, and if this be more than the current consumed in the translating devices, current will again flow into the battery and the lever 28 will be swung in a counter-clockwise direction with a velocity dependent upon the 95 rate of charge of the battery, and if this keep up long enough, the contact will again be completed and the coil 35 again brought into action, and if the current now be taken from the battery the lever 28 will be moved in a 100 clockwise direction a distance dependent upon the amount of current taken from the battery and if this be only a short distance, not even approaching the position shown in the drawing, and the charge of the battery be nearly or quite exhausted this voltage will fall somewhat and this will allow the lever 26 to be moved in a right-handed direction by the spring 27 and the lever 28 will immediately assume the position shown 105 in the drawing resetting the measuring mechanism to deliver to the battery its full normal charge before any diminution in its rate will be caused. It is, therefore, evident 110 that this embodiment of my invention allows 115 a given charge to be delivered to the battery and that incoming and outgoing battery currents are integrated and if at any time, for any reason, the battery voltage shall fall 120 slightly below the normal, the mechanism 125 130

will reset to deliver to the battery a full normal charge before any diminution in charging rate is caused, and therefore, this invention is applicable to the economical 5 charging of storage batteries having the characteristic of a straight line charging curve after the normal charging voltage is reached.

The operation of the modification shown 10 in Fig. II may be readily followed from the operation of Fig. I, the only alteration being that the solenoid 13 is in series with the storage battery and affected only by battery current in Fig. II, whereas the solenoid 13 in 15 Fig. I as above described is affected by a total generator output.

I do not wish in any way to limit myself 20 to any of the details of constructions or exact mode of operation of my invention given in this specification, the aim of which is merely to describe one type of system embodying the essentials of my invention which is as set forth in the following claims:

1. The combination with a generator; of 25 a storage battery charged thereby; and means for automatically quantitatively controlling the charge independently of the voltage across said battery under certain conditions and dependent upon the voltage 30 of said battery under other conditions.

2. The combination with a generator; of 35 a storage battery charged thereby; automatic means for controlling the generator; and means whereby said automatic means is affected by the quantitative charge delivered to the battery independently of fluctuations in the charging voltage, including means whereby the operation of the same is also affected by the discharging voltage.

40 3. The combination with a generator; of a storage battery charged thereby; automatic means for controlling the generator in series in the generator circuit; and means for varying the operation of said controlling 45 means depending upon the charge furnished to the battery, and including means for varying the operation of said controlling means dependent upon the battery voltage.

50 4. The combination with a generator; of

a storage battery charged thereby; automatic means for regulating the generator; means for varying the operation of said regulating means in accordance with current delivered to and taken from the battery; 55 and including means for affecting the operation of said last mentioned means affected by battery voltage.

5. The combination with a generator; of 60 a storage battery charged thereby; a regulator for the generator; quantitatively metering means operated by current flowing into and out of the battery for affecting the generator regulator; and means whereby the metering means is affected by changes in 65 battery voltage.

6. The combination with a generator; of 70 a storage battery charged thereby; a regulator for the generator; quantitatively metering means operated by current flowing into and out of the battery for affecting the generator regulator; and means whereby the metering means is readjusted by changes in battery voltage.

7. The combination with a generator; of 75 a storage battery; a translation circuit; a regulator for the generator; quantitative metering means responsive to the charging current from the generator to the battery and also to the discharging current from 80 the battery to the translation circuit; and means whereby said metering means may vary the operation of the regulator, including means for controlling the operation of said last mentioned means operating upon 85 changes in a characteristic of the battery.

8. The combination with a generator; of 90 a storage battery charged thereby; automatic means for regulating the generator; and means for varying the operation of the regulating means including a high resistance coil arranged in open circuit across the generator; and metering mechanism for closing and opening said circuit including an electromagnet in shunt across the battery.
